UNITED STATES PATENT OFFICE.

MICHAEL E. SULLIVAN, OF NEW BEDFORD, ASSIGNOR OF ONE-HALF TO
GEORGE DRAPER & SONS, OF HOPEDALE, MASSACHUSETTS.

RING-SPINNING FRAME.

SPECIFICATION forming part of Letters Patent No. 307,880, dated November 11, 1884.

Application filed December 16, 1883. (No model.)

To all whom it may concern:

Be it known that I, MICHAEL E. SULLIVAN, of New Bedford, county of Bristol, and State of Massachusetts, have invented an Improvement 5 in Ring-Spinning Frames, of which the following description, in connection with the accompanying drawing, is a specification.

This invention has for its object to effect the twisting of the yarn prior to its arrival at 10 the traveler, which acts to wind the yarn upon the rotating bobbin.

The invention herein contained consists, essentially, in a spindle having a ring or race attached thereto below the bobbin and provided with a traveler, and means to support 15 said spindle, combined with a ring-rail and a ring, and a traveler adapted to be moved on it by the drag of the yarn, the latter traveler, by falling behind the speed of the spindle and 20 its attached bobbin, acting, as usual, to wind the yarn upon the bobbin, while the ring and traveler carried by or rotated with the spindle twists the yarn.

The drawing represents one of my improved 25 spindles and attached ring and traveler secured to a foot-step rail, a bobbin, a ring-rail, and ring and traveler, part of a roller-beam, a guide-board, an attached yarn-guide, and the lower one of the usual front rollers common to ring-spinning frames, the said roller, 30 roller-beam, guide-board, ring and step rails being in section, a part of the bobbin being broken away to show the spindle. The under front roller, *a*, yarn-guide *a'*, guide-board *a''*, roller-beam *a''*, ring-rail *b*, ring *b'* thereon, 35 its traveler *b''*, ring-holder *b'''*, step-rail *c*, nut *c'*, spindle-support *c''*, spindle *c'''*, whirl *c''''* thereon, bobbin *c''''*, and driving-band *d*, are and may be all as usual in ring-spinning 40 frames, and preferably the spindle-support will contain a movable or yielding bolster of the Rabbeth class.

In accordance with my invention, the spindle is provided with a ring or race, *e*, which I 45 shall denominate as the "twisting-ring," it receiving, supporting, and guiding a twisting-traveler, *e'*, which receives the yarn *y* directly from the yarn-guide *a'*, the said yarn extending from the said guide down through

the ring *b'*, thence through the traveler or eye *e'*, and up through the winding-on traveler *b''* to the bobbin *c''*. The twisting-ring *e* rotates at the same speed as and in unison with the bobbin, but the twisting-traveler or eye *e'* falls behind or does not rotate as fast as the 55 ring, for its movement is retarded through the friction of the winding-on traveler *b''* on the usual ring, *b'*. It is well understood that it is necessary for the winding-on traveler to travel at a less speed than the bobbin, in order to effect the winding of the yarn. The heavier the traveler *b''* the harder and closer the winding, yet in ordinary ring-spinning frames, wherein the yarn is not fully twisted between the single traveler carried by the ring-rail 60 and the guide-eye or front rolls, the traveler has to be made lighter than if the yarn were fully twisted before reaching the winding-on traveler. The normal tendency of the twisting-traveler to travel at the same speed as the 65 twisting ring and spindle so acts upon the yarn as to cause it to assist the winding-on traveler in its movement on the ring *b'*, thus enabling the employment of a much heavier winding-on traveler, which is of great advantage, both in regulating the draft or tension on 70 the yarn and also the hardness of the yarn wound on the bobbin; and it also lessens wear of the traveler on the ring. The two travelers described receiving the yarn, as shown, 75 have a tendency to equalize the strain or tension on the yarn as the latter is being wound from the empty bobbin to the full diameter of the yarn load, and vice versa, or at the bottom and top of the traverse, for the extra 80 strain exerted at such times upon the yarn draws the twisting-traveler against the twisting-ring with greater force, thus inclining it to travel more nearly at the speed of the twisting-ring and spindle, at which time the twisting-traveler acts with greater power upon the 85 yarn, and consequently upon the winding-on traveler, and starts and carries it forward, thus decreasing the tension. Twisting the 90 yarn before it reaches the winding-on traveler *b''* enables the said traveler to be made heavier than were the yarn passed directly through the said traveler from the yarn-guide.

The ring b' may be of any usual construction, as may also be the traveler b^2 . The ring may be placed in a holder at the upper side of the ring-rail. The race of the ring may be 5 inclined to face the bobbin, substantially as in United States Patent No. 24,681.

I do not desire to limit my invention to the particular ring and traveler e^e' , as instead of the said devices I may employ a ring of any 10 other well-known shape, with a suitable or other well-known traveler thereon about over or against which the yarn is held, and, if desired, the race of the ring may be as in United States Patent No. 24,681, or No. 180,611, or 15 No. 204,832, without departing from my invention.

The ring-rail may be moved vertically in any well-known manner and by well-known appliances.

20 I do not broadly claim a main and an auxiliary ring, both of which are fixed or do not

rotate; nor do I broadly claim a ring fixed with relation to the spindle, but above the base of the bobbin and always occupying the same position with relation to the stationary ring. 25

I claim—

A rotating spindle provided with a twisting ring or race attached thereto below the bobbin, and a twisting-traveler for the said twisting-ring combined with a movable ring-rail, a ring thereon, and a winding-on traveler on the ring attached to the rail, the said travelers being adapted to receive the yarn and to operate substantially as described. 30

In testimony whereof I have signed my 35 name to this specification in the presence of two subscribing witnesses.

MICHAEL E. SULLIVAN.
